E. B. CROCKER.

GAGE SOCKET.

APPLICATION FILED JUNE 25, 1920.

1,376,860.

Patented May 3, 1921.

Ernest B. Burken Inventor
By his Attorney Samuel E. Darby

UNITED STATES PATENT OFFICE.

ERNEST B. CROCKER, OF STRATFORD, CONNECTICUT, ASSIGNOR TO MANNING,
MAXWELL & MOORE, INC., OF NEW YORK, N. Y., A CORPORATION OF NEW
JERSEY.

GAGE-SOCKET.

1,376,860.

Specification of Letters Patent.

Patented May 3, 1921.

Application filed June 25, 1920. Serial No. 391,793.

To all whom it may concern:

Be it known that I, ERNEST B. CROCKER, a citizen of the United States, residing at Stratford, county of Fairfield, State of Connecticut, have made a certain new and useful Invention in Gage-Sockets, of which the following is a specification.

This invention relates to gage sockets, and particularly to means for securing and attaching the socket piece to the gage case.

The object of the invention is to provide a simple and inexpensive gage socket and construction which is strong and rigid and whereby the necessity for employing expensive castings is avoided.

A further object of the invention is to provide a gage socket structure which permits the employment of plain stock and material, and wherein the socket piece is efficiently 20 and rigidly held against lateral or rotative displacement.

A further object of the invention is to provide a socket gage structure which permits the use of drawn or stamped out cases with 25 in which the gage elements are to be carried.

Other objects of the invention will appear more fully hereinafter.

The invention consists substantially in the construction, combination, location, and arrangement, all as will be more fully herein-after set forth as shown in the accompanying drawing, and finally pointed out in the appended claims.

Referring to the drawing,—

Figure 1 is a face view of a gage case with the top cover plate removed therefrom showing the application thereto of a gage socket embodying and in accordance with my invention.

Fig. 2 is a view in section on a plane indicated by the line 2, 2, Fig 1, looking in the direction of the arrows.

Fig. 3 is a view in section on the line 3, 3, Fig. 1, looking in the direction of the arrows.

Fig. 4 is a view in section on the line 4, 4, Fig. 3, looking in the direction of the arrows.

Fig. 5 is a broken view in section on the line 5, 5, Fig. 2, looking in the direction of the arrows.

Fig. 6 is a view showing plate 17 on the outside of the casing.

In carrying out my invention I employ a casing 6, which is drawn or stamped out

into cup-shape, and within which the gage movement is to be mounted. In the peripheral wall of the casing I form a rectangular opening indicated at 7, Figs. 2 and 4. This opening extends from the edge of the casing toward, but not entirely to the full depth of the peripheral wall of the cup, 55 leaving the boundary side edges 8 and bottom edge 9. The socket piece which I employ is made from plain stock material, such for example, as Tobin bronze, steel, or other material, according to the uses to which the 60 gage is to be put and the character of the pressure medium to be employed in connection therewith.

In practice I prefer to construct the shank 10 of this socket piece of polygonal shape in cross section. A convenient form is to employ a rectangular shaped socket piece as plain stock commonly comes in that shape. The stock material is cut off to the required length to form a socket piece, and the end 70 portion thereof is exteriorly threaded as indicated at 11 for attachment to the pipe connections to the source of the pressure medium. A kerf or slot 12 is cut into the shank portion 10 of the socket piece at its 75 inner end to afford means for receiving and anchoring the end of the Bourdon tube 13. A longitudinally extending passage 14 is formed through the socket piece to communicate with the kerf 12 and with the 80 Bourdon tube when anchored therein. An annular groove 15 is cut in the shank portion 10 of the socket piece, and this groove may be conveniently cut at the same time that the screw threads 11 are applied to the 85 socket piece. The depth of the annular groove 15 should be such as to permit the cylindrical portion 16 of the stock of the socket piece left by the annular groove to fit snugly between the edges 8 of the rectangular opening 7 in the wall of the casing, permitting the boundary edges 8 of said opening to enter the annular slot 15 on opposite 90 sides of the socket piece and permitting the boundary edge portion 9 of said opening to enter the annular slot 15. By reason of the fact that the walls of the annular slot 15 lie in straight planes transverse to the longitudinal axis of the socket piece, whereas the peripheral wall of the cup-shaped case 100 is curved, it will be seen that it is necessary

105

in inserting the socket piece in place to spring the boundary edges of the opening 7 in the curved wall of the case into the annular slot 15. This, however, affords a most 5 substantial connection between the socket piece and the case, the binding of the walls of the case opening in the annular slot serving to rigidly hold the socket piece against longitudinal or lateral displacement. In 10 order to prevent axial displacement of the socket piece I employ a securing plate 17, which I preferably stamp up out of sheet metal, and in which I form a polygonally shaped opening corresponding to the cross 15 sectional contour of the shank portion of the socket piece as indicated at 18, and which stamping is fitted upon the shank portion preferably with a snug fit. This stamping is shaped to conform to the curvature of the 20 wall of the case 6 so as to fit thereagainst and to which the stamping may be secured in any suitable manner, as for instance, by the screw studs 19. In practice the securing plate is placed on the inside of the case 25 wall, and the ends of the securing screws 19 are received through threaded openings which are stamped in the securing plate. I do not desire to be limited, however, with respect to the location of the securing plate 30 or stamping 17, as the same might be equally well located on the outside of the casing. While I have shown a socket piece of rectangular shape, it is also to be understood that my invention is not to be limited 35 or restricted to this particular shape, although I find it convenient to employ a rectangularly shaped socket piece for the reason that stock material is easily obtainable in the market having this shape.

40 It will be observed that the securing plate 17 mounted and attached as above described retains the socket piece efficiently against axial rotative displacement.

A structure of socket piece and the manner of its mounting in a gage case as shown 45 and as above described not only secures great simplicity but also rigidity and sturdiness, and machining work is reduced to a minimum, thereby greatly lessening the cost of 50 construction. Moreover, I am enabled to avoid the use of castings which are difficult to make and expensive to prepare and which greatly increase the cost of construction as well as the weight of the finished gage. I 55 am also enabled to employ gage cases which are drawn or stamped out of sheet metal, thereby reducing weight as well as expense of manufacture. I also avoid the necessity for machining the seating surfaces such as 60 are ordinarily required in fitting socket pieces to cast metal gage cases.

65 Where the gages are required for use in connection with ammonia gases it is the common practice to employ socket pieces made of steel instead of bronze and a socket

structure and means for attaching the same embodying my invention lends itself to the use of steel socket pieces as the steel stock therefor is readily obtainable in the desired shape in the market and no castings are 70 required.

Whatever may be the material employed for the socket piece it will be seen that I provide an exceedingly simple, sturdy, rigid and economical mounting of the socket piece 75 which secures strength and rigidity and greatly reduces the weight as well as the cost of manufacture.

Having now set forth the objects and nature of my invention, and a construction 80 embodying the principles thereof, what I claim as new and useful and of my own invention, and desire to secure by Letters Patent is,—

1. In a gage socket structure, the combination with a gage case having a slot in its peripheral wall, of a socket piece fitting in said slot and having an annular groove into which the edges of said slot extend whereby said socket piece is maintained in position. 90

2. In a gage socket structure, the combination with a gage case having a slot in its peripheral wall, of a socket piece fitting in said slot and having an annular groove into which the edges of said slot extend, 95 and a plate fitting over the socket piece and secured to the wall of the case.

3. In a gage socket structure, the combination with a gage case having a slot in its peripheral wall, of a socket piece having a shank portion of polygonal shape in cross section to fit in said slot, said polygonal shaped shank portion having an annular groove into which the bounding edges of said slot extend. 100

4. In a gage socket structure, the combination with a gage case having a slot in its peripheral wall, of a socket piece having a shank portion provided with one or more plane surfaces to fit in said slot, said shank portion having an annular groove to receive the bounding edges of said slot. 110

5. In a gage socket structure, the combination with a gage case having a slot in its peripheral wall, of a socket piece having a shank portion provided with one or more plane surfaces to fit in said slot, said shank portion having an annular groove to receive the bounding edges of said slot, and an anchor plate engaging over said shank portion and secured to the wall of the case. 115

6. In a gage socket structure, the combination with a gage case having a slot in its peripheral wall, of a socket piece having a shank portion provided with one or more plane surfaces to fit in said slot, said shank portion having an annular groove to receive the bounding edges of said slot, and an anchor plate having an opening therethrough conforming in outline to the shape of the 120 125 130

shank portion of the socket piece, and means to secure said anchor plate to the wall of the case.

7. In a gage socket structure, the combination with a gage case having a circular wall, said wall having a slot formed therein, in combination with a socket piece having an annular straight walled groove, said socket piece fitting in said slot and the edges 10 of said slot received in said groove.

8. In a gage socket structure, the combination with a gage case having a circular wall, said wall having a slot formed therein, in combination with a socket piece having an 15 annular straight walled groove, said socket piece fitting in said slot and the edges of said slot received in said groove, and an anchor plate fitting the contour of the circular wall of the case and secured thereto, and 20 engaging said socket piece.

9. In a gage socket structure, the combination with a gage case having a circu-

lar wall, said wall having a slot formed therein, in combination with a socket piece having a shank portion formed with one or 25 more straight side surfaces fitting in said slot, said shank portion having an annular groove, the bounding edges of said slot fitting in said groove.

10. In a gage socket structure, the combination with a gage case having a circular wall, said wall having a slot formed therein, in combination with a socket piece having a shank portion formed with one or more 30 straight side surfaces fitting in said slot, 35 said shank portion having an annular groove, the bounding edges of said slot fitting in said groove, and an anchor plate engaging said shank portion and secured to the wall of the case. 40

In testimony whereof I have hereunto set my hand on this 22nd day of June, A. D. 1920.

ERNEST B. CROCKER.
